United States Patent Office

LEANDER LEHMAN, OF HARRISBURG, PENNSYLVANIA.

Letters Patent No. 78,976, dated June 16, 1868.

IMPROVED BOTTLE-LOCK.

The Schedule referred to in these Letters Patent and making part of the same.

TO ALL WHOM IT MAY CONCERN:

Be it known that I, LEANDER LEHMAN, of Harrisburg, in the State of Pennsylvania, have invented a new and improved Mode of Locking and Corking Bottles; and I do hereby declare that the following is a full and exact description thereof, reference being had to the accompanying drawings, and to the letters of reference marked thereon.

The nature of my invention consists in providing the bottle with a top made of brass or other material, which is locked upon the neck of the bottle by means of a band passing round the neck, below the "lip," which band is locked by a small screw-bolt, having a head fitted and shaped for and which can be opened only by a key. This is done by means of a flange or lip extending out from the band *a* on three sides of the nut, and fitting closely to each of these three sides, so that the nut cannot be turned, but remains fixed and stationary, or the thread for the screw-bolt may be cut in the projecting part of the band *a*, and the nut dispensed with.

The lock is made water-tight by an India-rubber ring, which is placed between the lock and bottle. This lock or "top" has a lid working on a hinge placed on top, inside of which lid is a small spring-lock, which, when the lid is pressed down, is fastened by a catch on the top of the "cap." The bottle is made water-tight, further, by a "rubber" plate being fastened on the under side of the said lid, which fits down tight on the top of the cap. The lid is opened by a key, and locks itself by being pressed down shut.

What I claim as my invention, and desire to secure by Letters Patent, is—

1. A self-locking bottle-stopper, when the cover is secured by means of a spring-lock and hasp, substantially as described.
2. Securing the same to the bottle by means of the band *a*, the ends of which are fastened together by the protected screw-bolt *g*, in the manner described.

LEANDER LEHMAN.
